INTERLOCKING BLOCK

Walter O. Nelson, Grand Forks, N. Dak.

Application October 9, 1950, Serial No. 189,105

1 Claim. (Cl. 46-25)

1

This invention relates to a toy and more particularly to a toy utilizing a plurality of blocks that may be arranged in various configurations, that may be stacked and interlocked in constructing various types of figures and designs.

An object of this invention is to provide a hexagonal toy block having radially disposed slots, the widths of which are substantially equal to the thickness of the block, the slots being associated with recesses used in interlocking projections on the face of the block to interlock the blocks.

Another object of this invention is to provide a plastic block provided with wings having recesses so as to provide flexibility to permit the blocks to be interlocked.

Other objects and advantages reside in the construction of parts, the combination thereof and the mode of operation, as will become more apparent from the following description.

In the drawings, Figure 1 is a top plan view of a block.

Figure 2 is a cross sectional view, taken substantially on the line 2-2 of Figure 1.

Figure 3 is a perspective view showing two interlocking blocks.

Figures 4 and 5 are schematic views illustrating two design lay-outs that may be constructed by the use of the blocks disclosed herein.

Referring to the drawings, the reference character 10 designates a block having six sides 12, each side being bisected by a radially disposed slot 14, the depth of the slots 14 being slightly less than half the perpendicular distance from the center of the block to the side. The width of the slot is greater, but not much greater, than the thickness of the block. Adjacent slots cooperate with two adjacent side portions to form a wing-like extension 16. Each of the wing-like extensions is provided with hollowed out cavities or recesses 20, one on each side thereof, leaving a reduced portion 22, as clearly shown in Figure 2. The thickness of the reduced portion is much less than the maximum thickness of the main body of the block. The sides 12 are bevelled at 24. Each of the wing-like extensions 16 is provided with two rounded recesses 30, one on each side. These recesses 30 cooperate with semi-spherical projections 32 to interlock blocks, as clearly shown in Figure 3. Each of the semi-spherical projections is offset from a center line of the nearest slot, which center line passes through the center of the block.

The thickness of each block is only a small fraction of the breadth of the block. The thickness may be on the order of ten percent of the breadth

2

of the block. The depth of each slot is slightly less than one-fourth the altitude of the block, as clearly seen from Figure 1. The distance of each projection 32 to the nearest slot is substantially equal to the distance from the recess 30 to the bottom of its slot.

In order to assemble the blocks by slipping one block into the recess of another block, the wing-like extensions are flexed sufficiently so as to permit the semi-spherical projections 32 to snap into position. The relative positions of the recesses 30 and the projections 32 are such that two projections on one block are seated in two recesses adjacent a slot in another block, the projections of said other block being seated in recesses in the first block, so that when two blocks are interlocked, four projections are seated in four recesses, thereby insuring a firm, rigid coupling of the blocks. It is to be noted that the blocks are interlocked when the blocks are in planes at right angles to each other and the slot of one block registers with the slot of another block, the two slots overlapping each other while the interlocking movement of the two blocks 25 is initiated.

Each block is provided at its center with an aperture 40, which may be used for supporting a shaft in the event it is so desired, which shaft may support pulleys, motors, reels, or any other rotatable or non-rotatable part. This permits the use of blocks in erecting frames to be used in a manner similar to toys generally known in the trade as "Tinker Toys."

The blocks lend themselves to the construction of numerous types of designs, two of which have been schematically shown in Figures 4 and 5. In Figure 4 the blocks have been arranged so as to suggest a hexagonal figure. In this particular figure the center block is used for supporting six vertically disposed blocks, each of which supports a block in the plane of the center block. The six vertically disposed blocks cooperate to form a hexagonal opening aligned with the center in the center block. The bevelled edges 24 of the six vertically disposed blocks are brought into contact with each other. By this arrangement the aperture formed by the six vertically disposed blocks is smaller than if the bevelled edges 24 were omitted. In Figure 5 the blocks have been arranged to form a parallelogram. In Figures 4 and 5 the blocks have been shown schematically for the purpose of illustrating uses to which the blocks may be put.

Although the preferred embodiment of the 55 device has been described, it will be understood

that within the purview of this invention various changes may be made in the form, details, proportion and arrangement of parts, the combination thereof and mode of operation, which generally stated consist in a device capable of carrying out the objects set forth, as disclosed and defined in the appended claim.

Having thus described my invention, I claim:

A block for use with a multiplicity of like blocks, said block having six sides, the thickness of the block being only a fraction of the width of the block, the sides being bisected by a slot having a width slightly greater but not much greater than the thickness of the block, said slots having a depth equal to slightly less than one-fourth of the altitude of the block, the slots from adjacent sides cooperating with adjacent portions of the sides to form wing-like extensions, said wing-like extensions being provided with recesses on each side so that the thickness of the wing-like extensions is thinner than the maximum thickness of the block, said slots being provided with rounded recesses, there being one recess on each side of the slot, each recess being located in a margin of the slot approximately at the midpoint thereof, the recess in one margin of the slot being located on one side of the block and the other recess of the slot being located

on the opposite side of the block, and semi-spherical projections extending outwardly from the side of the block, the projections on one side of the block being offset from the projections on the opposite side of the block, the amount of offset corresponding to the offset distance between the rounded recesses of a slot, the projections being located between the slots in the center of the block, the distance of each projection from the bottom of the nearest adjacent slot being substantially equal to the distance from the rounded recess to the bottom of the slot, said semi-spherical projections being adapted to be seated in recesses of like blocks for interlocking the blocks.

WALTER O. NELSON.
